US0D1084035S

(12) **United States Design Patent** (10) Patent No.: **US D1,084,035 S**
(45) Date of Patent: ** Jul. 15, 2025

(54) **FLUID END**

(71) Applicant: **GD Energy Products, LLC**, Tulsa, OK (US)

(72) Inventors: **Konner Casey Kay**, Broken Arrow, OK (US); **Vadim Kachkovskiy**, Spring Mills, PA (US)

(73) Assignee: **GD ENERGY PRODUCTS, LLC**, Tulsa, OK (US)

(**) Term: **15 Years**

(21) Appl. No.: **29/863,497**

(22) Filed: **Dec. 20, 2022**

(51) LOC (15) Cl. **15-04**

(52) U.S. Cl.

USPC **D15/21; D15/7**
